PLANETARY TRANSFER MACHINES

Alan P. L. Thomas, Solihull, England, assignor to Edward J. Skinner Limited, Solihull, Warwickshire, England

Application April 25, 1957, Serial No. 655,073

5 Claims. (Cl. 198—19)

This invention has reference to planetary transfer machines of the kind comprising a number of platens which are displaceable internally and at timed intervals along a fixed bed and each of which is provided with a clamp or equivalent fitting for holding a workpiece thereon so that, as the platens are displaced upon the bed to and through a succession of different stations, the workpieces held thereon may be subjected to a predetermined sequence of operations, such as drilling, boring, reaming and/or cleansing, by tools or appliances installed and operating at the said stations.

The principal object of the present invention is to provide an improved planetary transfer machine in which the predetermined sequence of operations may be performed on each workpiece held upon a platen, at any number of different positions anywhere around the workpiece, during a single progression of the said workpiece through the several stations and without having either to alter the position of the workpiece on the platen or to turn the platen upon the bed of the machine.

Further objects of the invention are to provide a machine wherein the first and final stations of each progression are adjacent one another so that a single operator may remove and replace a treated workpiece by a fresh workpiece between two successive displacements of the corresponding platen; to minimise the total number of platens that need be provided in the machine to enable a predetermined sequence of operations to be performed on each of the workpieces; to enable the number and the arrangement of the stations to be varied as desired, and to minimise the floor space occupied by the machine.

In accordance with the present invention, a planetary transfer machine of the kind referred to comprises a number of identical platens which are disposed in a common plane with each platen occupying a different one of a number of stations arranged around the periphery of a polygonal area having at least four straight sides, each side being of a length equal to, a multiple of a platen dimension and the number of platens being one less than the number of stations so that one station is unoccupied by a platen and the platens are adapted to be progressed from station to station along each of the sides in succession.

Preferably, the unoccupied station is located at a corner of the polygonal area so that all the platens occupying the remainder of the stations in one of the two sides converging at the corner, may be displaced simultaneously thereby removing the platen from the station at the opposite end of the said one side; consequently, the platens in the next adjacent side may be displaced simultaneously and so on around the whole of the said area until all the platens have been displaced from one station to the next adjacent station in the direction of progression.

The bed of the machine may be built up from a number of identical corner units and a number of identical intermediate units so that by varying the number and/or arrangement of the said units, the number and arrangement of the stations may be varied as desired.

2

In order that the invention may more readily be understood and carried into practice, reference will now be made to the accompanying drawings, wherein:

Figure 1 is a perspective view of a planetary transfer machine, some of the control apparatus and work-treating mechanism having been omitted for the sake of clarity.

Figure 2 is a plan of the machine shown in Figure 1, all the control apparatus and work-treating mechanism having been omitted.

10 Figure 3 is an underside perspective view on an enlarged scale, of a platen.

Figure 4 is a sectional elevation, on the same scale as Figure 3, of the top of one side of the machine shown in Figure 2, and

15 Figure 5 is a section, on a still larger scale, along the line V—V, Figure 2.

The machine shown in the said drawings comprises a bed 1 which is disposed around the periphery of a square floor-space area and is built up from four identical units

20 2 each of which is located at a corner of the bed, and eight identical units 3 which are of the same depth as the corner units and two of each of which are located in the bed intermediate two of the said corner units. The units are secured together in face-to-face abutment, 25 each two abutting faces being formed with registering keyways both of which are engaged by a corresponding key 5 (see Figure 4) to ensure that the units in each of the four sides of the bed are in exact alignment.

The machine also comprises eleven platens 4 each of 30 which is supported upon the head of a corresponding one of the corner or intermediate bed units 2, 3, is provided with a clamp, jig or equivalent fitting (not shown) adapted to receive and locate a workpiece on the upper face of the platen, and is capable of being displaced upon 35 guide or keeper plates 6 of uniform thickness, secured upon the top of the corner and intermediate units 2 and 3, from one unit on to an adjoining unit. Since the said corner and intermediate units are of the same depth and the plates 6 are of uniform thickness, the platens are located in a common horizontal plane.

Each corner and intermediate bed unit forms part of a different work-treating station, each of which (with one exception) also includes mechanism or apparatus, with one or more electrically-driven drills or other machine tools 7 (see Figure 1) and/or washing or similar work-cleansing means 8, and a master control cabinet 9 or subsidiary control cabinet 10; the station 1a which does not include any such mechanism or apparatus is a loading station where the workpieces are mounted in and removed 45 from the clamps or like fittings on the platens, by an operator working at the said station, from where he is also able to operate push-button switches 11 of the master control cabinet.

Since there are twelve separate stations and only eleven 50 platens, obviously, at any given instant when each platen is occupying a corresponding one of the said stations, the twelfth station is not so occupied. Consequently, by displacing a platen from an adjacent station into an unoccupied station, each of the platens may be progressed to 55 and through each of the twelve stations in succession and in sequence. Further, if, as shown in Figures 1 and 4, the unoccupied station is always one of the four corner stations, then all the platens in either of the two sides of the machine which converge to the corner at which the 60 said unoccupied station is situated, that is the platens on the three remaining bed units in the said side, may be displaced simultaneously by displacement of the platen occupying the corner station at the opposite end of the side; as a consequence, during each cycle of operations, the 65 platens are progressed through the several stations in four groups each consisting of three platens, the leading platen of the group displaced at the commencement of the 70

cycle; being the trailing platen in the group displaced at the end of the cycle. The successive displacement of the four separate groups is initiated and timed by the master control cabinet which also controls the subsidiary cabinets in such a manner that, at the termination of the displacement of each group, the machine tool or tools and/or other work-treating apparatus included in the three stations into which the platens are displaced, are put into operation for periods controlled by the respective subsidiary cabinets 10.

As each platen carrying a treated workpiece moves into the loading station 1a, the said workpiece is removed by the operator and replaced by a fresh untreated workpiece so that as the platen supporting the fresh workpiece is progressed to and through the remaining eleven stations in succession, it is subjected to one or more drilling, boring, reaming, washing or similar treatments during each cycle of operations. As each platen and its supported workpiece is displaced into each corner station, a different zone of the periphery of the said workpiece is presented to the external periphery of the bed and is, therefore, accessible to the machine tools, such as the drills 7, mounted upon the cabinets 9 and/or 10 around and externally of the said bed. Since an overhead machine tool, such as the drill 7a may be included in the apparatus installed at any of the several stations, the tops of the workpieces may also be subjected to any desired number of treatments as the platens progress through the several stations from and back to the loading station 1a.

Each of the bed units 2 and 3 is a hollow structure and is formed with an internal transverse partition 12 (see Figures 4 and 5) in the vicinity of its upper end so that the unit is divided into an upper compartment 13 and a lower compartment 14. Immediately below the partition, vertical walls 15 and horizontal walls 16 isolate auxiliary chambers 17 from the lower compartment; in each intermediate unit, the two auxiliary chambers extend respectively along the inner and outer walls of the unit and open to both transverse walls; in each corner unit, one auxiliary chamber extends along the two adjacent outer walls of the unit and opens to the other two transverse walls, whereas the other auxiliary chamber extends between and opens to the two transverse walls at the converging ends of the latter. Hence, the chambers form two continuous ducts which extend respectively around but inside the internal and external peripheries of the bed for accommodation of electric wiring and/or compressed air lines, the units being formed with windows or apertures 18 (see Figure 1) to permit access to the said ducts.

Flanges 19 extending inwardly of and along the length of the upper edges of the internal walls of each intermediate unit, provide supports for the keeper or guide plates 6 which are of the same length as and are fixed upon the said flanges; the plates are wider than the flanges and overhang the inner edges of the latter. Similarly, plates 6 are fixed upon the upper edges of the two outer walls of each corner unit and upon a pillar 20 provided in the angle between the converging ends of the other two transverse walls; the plates of the corner units also overlap their respective flanges and posts.

Each platen (see Figures 3-5) consists of a square crown 21 which is of the same dimensions as the top of each bed unit and has wear plates 22 embedded in the peripheral zone of its underside, which wear plates seat upon and are adapted to slide along the upper faces of the keeper plates 6. A square block 23 depends from the underside and centrally of the crown 21, the block being of smaller area than the crown and having a groove 24 formed in and along each of its four sides. The block passes between the adjacent edges of the keeper plates 6 and the overhanging portions of the plates engage the grooves in opposed sides of the block thereby retaining the platen upon the bed of the machine in a manner which prevents the platen from rotary movement relatively to the said bed but permits the said platen to slide along the

plates from station to station and to change its direction of travel through ninety degrees as it is displaced from each corner station.

As shown in Figure 3, two pairs of pockets 25, 25a are formed in the underside of each platen block, the pockets of each pair being located in a different diagonal of the block. A female coned seat 26 is secured within each pocket and each bed unit is provided with two vertical plungers 27 each having a tapered head 27a; the plungers are reciprocable within liner bushes 28, 29 provided on the partition 12 and chamber walls 15 respectively and their lower ends are connected by cranked links 30 and straight links 31 to the outer end of the piston rod 32 of a double-acting pneumatic cylinder 33 journalled upon a fixed platform 34 provided in and diagonally of the lower compartment 14. The plungers are so located within the corresponding bed unit that when driven upwardly by displacement of the piston rod inwardly of the cylinder, and when a platen is displaced on to the top of the said unit, the tapered plunger heads engage respectively with the tapered seats of one of the pairs of pockets thereby locating the platen in a predetermined position relatively to the bed unit and to the tool or tools and/or other work-treating apparatus included on the same station. The tapering of the seats facilitates the engagement of the plungers with the seats and compensates for any wear that may take place between their mating surfaces. The arrangement of the cranked and straight links is such that the links are locked against return movement so that the plungers are unable to recede until admission of compressed air to the cylinder forces the piston rod outwardly of the said cylinder. The provision of the two pairs of pockets in each platen enables the plunger bushes to be located in identical relative positions in each corner unit and each intermediate unit because as each platen progresses from one side of the bed into an adjacent side in which the bed units are turned through ninety degrees relatively to the units in the preceding side, the plungers are adapted to engage a different one of the two pairs of seats (see Figure 2).

For displacing the groups of platens along the sides of the bed, two parallel walls 35 are provided upon the upper face of the transverse partition of each bed unit so as to form a channel 36 symmetrically of one of the transverse centre lines of the unit. The channel ends open respectively to opposed side walls of each upper compartment 13 and in three adjacent bed units (namely the two intermediate units and one corner unit) of each side of the bed, the channels are arranged in longitudinal alignment (see, Figure 4) and house a corresponding double-acting pneumatic cylinder 37 of which the piston-rod 38 has secured on its free or outer end, a plate 39 of which the upper edge is provided with a hook or lug 40 adapted to engage behind an edge of the block on the underside of the platen located on the corresponding corner unit, when the piston rod is driven to the limit of its travel outwardly of the cylinder. Consequently, when the piston is forced inwardly of the cylinder by the admission of compressed air to the said cylinder, the platen located on the said corner unit is adapted to be displaced, after the retraction of the plungers from the tapered seats, along the said side of the bed on to the adjacent intermediate unit. The plungers engaging the platens on the two intermediate units are retracted simultaneously with the plungers engaging the platen on the corner unit, with the result that the displacement of the latter platen also displaces the other two platens and the leading platen is progressed on to the previously unoccupied corner platen in the next adjacent side of the bed. A groove 41 formed in and lengthwise of each channel is engaged by the lower edge of the plate 39 to ensure that the plate travels along a straight path within the channel.

Although the invention has been described with refer-

ence to a planetary transfer machine comprising four corner bed units and eight intermediate bed units arranged along the four sides of a square floor space area and surmounted by eleven platens, it is to be understood that it is not restricted to such a machine since the number of units in its sides may be increased or decreased as desired depending upon the number of treatments to which each workpiece is to be subjected, and/or the units may be arranged along the sides of a polygonal floor space area having more than four straight sides.

Since all the platens are located in a common plane upon the top of the machine bed and are displaced intermittently to and through each of the stations in succession from and back to the loading station 1a, they and the workpieces carried thereon are always visible and readily accessible; also, a separate workpiece may be mounted upon each and every one of the platens and each and every one of the said workpieces may be subjected to one or more treatments during each operational cycle. Further, since the bed of the machine is disposed around a polygonal floor space, the area occupied by the machine is reduced to a minimum.

I claim:

1. A planetary transfer machine comprising a bed defining a polygonal area having straight sides of which adjacent sides are at right angles to one another, said bed consisting of a number of corner units which are identical to one another and a number of intermediate units which are identical to one another, each unit having a square platen supporting head, the heads of the said units being disposed in edge-to-edge abutment in and along the sides of the said area, a number of identical square platens less than the total number of corner and intermediate units, each platen being supported upon a corresponding one of the heads, being of the same area as each of the said heads and coinciding with said corresponding head, means for displacing the platens from bed-unit to bed-unit along each of the said sides in succession, and means for individually locking the platens upon said heads between successive displacements.

2. A planetary transfer machine comprising a number of square platens and a bed defining a polygonal area having straight sides of which each adjacent two sides are at right angles to one another, and are equal in length to a multiple of the length of a platen, said bed consisting of a number of corner units which are identical to one another and a number of intermediate units which are identical to one another, each unit having a square head of equal area to each of said platens, the said heads being disposed in a common plane and in edge-to-edge abutment in straight lines around the sides of said area, each head having flanges projecting inwardly of the head from opposed edges to form a guideway and support the platens, rails secured to said flanges, each platen having a square dependent projection which engages in said guideway, a groove formed around the root of each projection, said groove being engaged by said rails to retain the platens on said bed but permit a displacement thereon, means for displacing said platens in groups consisting of platens disposed on the heads of each one of said sides, and means for locking each platen between successive displacements.

3. A planetary transfer machine comprising a bed and a number of platens supported on said bed, all of said platens being square, identical with one another, formed with a dependent square projection, having a groove formed around the root thereof four pockets formed respectively in corners of the projection and opening to the face thereof, said bed consisting of a number of corner units identical to one another and disposed respectively at the corners of a polygonal area, and a number of intermediate units identical to one another and disposed between corner units along the sides of said area, said sides being equal in length to a multiple of the length of a platen, each of the units having a square platen-receiving head of equal area to each of said platens and flanges ex-

tending inwardly from opposite sides to form a guideway into which one of said square projections is received, rails secured to said flanges and engaging in said grooves, to retain the platen on the head but permit displacement therefrom onto the next adjacent head, the number of platens being less than the total number of units, means for displacing said platens along said bed in groups to move a leading platen of a group onto a vacant corner unit and remove a trailing platen of said group from a corner unit so as to vacate said corner unit, and means comprising a pair of plungers disposed in each unit registerable with one of said pockets, and displaceable by a pressure-fluid cylinder for locking said platens individually and relatively to said bed between successive displacements.

4. A planetary transfer machine comprising a bed made up of a number of corner units identical with one another and a number of intermediate units identical with one another, each unit having a square head formed with flanges extending inwards from opposite sides thereof to define a guideway therein, a channel in each head between said flanges, and rails secured to and overhanging said channel, said machine further comprising a number of square platens identical with one another, each having a square projection dependent from one face, a groove formed around the root of said projection, a pocket formed in each corner of said projection, and opening to the face thereof, said number of platens being less than the total number of units, each platen being of equal area to each of the units, supported on and coinciding with the head of a corresponding one thereof, said projection being received in the guideway between flanges and said rails engaging in said grooves, all of the units being arranged with their heads in edge-to-edge abutment so as to form an endless support for said platens and an endless guideway for the projections therefrom around the periphery of a polygonal figure, each side of said figure being equal in length to a multiple of the length of a platen and at right angles to adjacent sides, means comprising a pair of reciprocable plungers provided in each unit for engagement with one of said pockets so as to lock a platen supported on each of said units to said units individually, and means for displacing the platens along the guideway from bed-unit to bed-unit comprising double-acting pressure fluid cylinders disposed in the channel formed in the several heads of the units, one of such cylinders being disposed in each of the sides, and a plate secured to the piston rod of each of said cylinders for engagement with the projection from the trailing one of a line of platens which is to be displaced so that by movement of a piston within the corresponding cylinder said trailing platen may be displaced from a corner unit on to the next adjacent unit and the leading one of said line of platens being moved onto the next corner unit.

5. A planetary transfer machine comprising a bed defining a polygonal area having straight sides of which each adjacent two sides are at right angles to one another, and a number of square platens, the bed consisting of a number of corner units identical to one another and a number of intermediate units identical to one another, said units all having square heads, said heads being arranged in edge to edge abutment in straight lines around the sides of said area, each of said lines of length equal to a multiple of the length of said platens each side being at right angles to adjacent sides, said heads lying in a common plane, a guideway formed around said area in said heads, each platen having a square projection engaging in said guideway being of equal area to each of said units, coinciding with a respective one thereof and being displaceable around said bed from unit to unit, a pocket formed adjacent each corner of said projection, means for displacing said platens, and means for individually locking said platens between successive displacements comprising a double-acting pressure fluid cylinder mounted in each unit, a pair of plungers reciprocable in

the head of each unit, a pair of links pivoted to the free end of the piston rod of each cylinder, a pair of cranked-links individually pivoted in each unit, one end of each of said cranked-links being pivoted to the free end of corresponding one of said piston-rod pivoted links and the other ends being pivoted respectively to said plunger, the latter being movable by the corresponding piston rod into engagement with one of said pockets to lock the platens to the bed and being immovable from the locked position

until the piston rod is returned, different ones of said pockets being engaged in adjacent sides of the bed.
